UNITED STATES PATENT OFFICE.

HARRY T. GOSS, OF RUTHERFORD, NEW JERSEY, ASSIGNOR TO J. EDWARD OGDEN, OF BROOKLYN, NEW YORK.

SPRING-HAMMER.

1,158,678.

Specification of Letters Patent.

Patented Nov. 2, 1915.

Application filed November 12, 1912. Serial No. 730,849.

To all whom it may concern:

Be it known that I, HARRY T. Goss, a citizen of the United States, and a resident of Rutherford, county of Bergen, and State of New Jersey, have invented certain new and useful Improvements in Spring-Hammers, of which the following is a specification, reference being had to the accompanying drawings, forming a part thereof.

My invention relates to percussive tools and it has special reference to such as embody a spring actuated striker and are known as spring hammers.

The object of my invention is to provide a simple and durable device of the aforesaid character that shall be portable, easy to operate, inexpensive to manufacture and embody a number of novel and important features which shall particularly adapt it for such uses as the drilling of stone, brick or concrete.

Other objects will be set forth hereinafter.

In the drawings: Figure 1 is a longitudinal section through its central plane, of a spring hammer constructed in accordance with my invention. Figs. 2 and 3 are transverse sectional plan views on the lines 2—2 and 3—3 respectively of Fig. 1. Fig. 4 is an elevation at right angles to Fig. 1, and Figs. 5 and 6 are transverse sectional plan views on the lines 5—5 and 6—6 of Fig. 1.

Like characters of reference designate corresponding parts in all the figures.

Referring to the drawings, the device here shown comprises a tubular body or barrel 11, a handle member 12, a tool holder or chuck 13, a hammer or striker 14, an actuating compression spring 15, a cam 16 and an operating crank or lever 17.

The tool holder or chuck 13 is affixed to the lower end of a rotatable cylindrical tube or quill 20. Its lower end projects in the form of a flange 18 beyond the bottom of the quill. Its upper end 19 is of smaller diameter and fits rotatively within the lower end of the tube or barrel 11. This lower end of the barrel 11 rests upon a shoulder on the chuck which takes the thrust due to the reaction of the tool.

The cam 16 has a notched periphery which gives it the general form of a ratchet. It is secured to a transverse shaft 25 at one side of the barrel. The shaft is supported in bearings 26 and 27 provided in the respec-

tive halves of a divided casing or housing 30 which incloses the cam.

The parts of the casing or housing 30 are provided with jaws 31 which are adapted to grip the tube or barrel 11 when the two parts of the housing are clamped together by machine screws or bolts 32. The crank or lever 17 may be secured to either end of the shaft 25 both ends of which extend materially beyond the bearings 26 and 27 for this purpose. The casing or housing is further provided with a hollow boss projection 35 which is co-axial with the barrel 11 and is adapted to receive and form a bearing for the quill 20. The casing is enlarged to provide a substantially annular recess 36, adjacent the boss 35 in which a ratchet 37 is located. This ratchet is affixed to the upper end of the quill which extends through the boss into the casing. The arrangement of parts is such that the quill is held in position by the ratchet 37 while the quill and ratchet together are free to rotate in the hollow boss 35 as a bearing.

A pawl carrier 40 is interposed between the ratchet 37 and the surface of the adjacent set of jaws 31. It loosely surrounds the barrel 11 and is provided with a projection 41 which has an upwardly projecting cam surface 42 and a pin 43 on which a pawl 44 is pivotally supported. The pawl is adapted to co-operate with the teeth of the ratchet 37 and is held in engagement with them by a spring 45.

The pawl support 40 is limited to one direction of rotation by a stationary stop 46 which is secured to the housing 30 and it is normally held in position by a spring 48. The hammer or striker 14 is slidably supported within the barrel 11 near the chuck 13 and is provided with a slot 50 which is directly opposite a slot 52 in the barrel 11.

The inner end of the hammer or striker is provided with a boss 54 which extends into one end of and centers the spring 15 which tends to hold the hammer or striker in engagement with the inner end of a drill or other tool 58. The shank 59 of the tool is square and extends through a square hole in the chuck 13. Any suitable structure which permits the longitudinal movement of the tool in the chuck but prevents the relative rotation of the two may be used.

The size of the cam 16 and the position of

the shaft 25 are such that the teeth of the cam extend through the slot 52 in the barrel and into the slot 50 in the hammer or striker. Furthermore, the arrangement of parts is 5 such that the teeth of the cam are adapted to engage the cam surface 42 of the pawl carrier 40.

The handle member 12 comprises a grip 60 supported between the forks 61 of a U-shaped or bifurcated projection in a well known manner. The handle member further comprises a split hollow portion 62 which is fitted onto the opposite end of the barrel from the chuck and is firmly clamped by a bolt 63 and further held in position by a set screw 64. The handle member is provided with a recess 65 which is open at one side as clearly shown in Fig. 5 and is adapted to receive a knurled adjusting nut 66. 10 The tension of the spring 15 depends upon the position of an adjustable stop 67 which is fitted into one end of the barrel 11 and is provided with a boss 68 which is opposite and corresponds to the boss 54 of the hammer or striker, the spring 15 being interposed and compressed between the hammer and the stop. 20

The stop is provided with a screw-threaded shank 69 onto which the nut 66 is screwed and which extends into a cylindrical hole in the handle member 12. This hole has a smooth bore and is only intended to guide the stop when it is adjusted longitudinally of the barrel by turning the nut 66. The 30 stop is prevented from rotating with the nut, by a pin 70 which extends through a transverse hole 71 in the handle member into a longitudinal slot or keyway 72 in the shank 69 of the stop. 35

One of the parts of the housing 30 is provided with a projecting lug 80 having a hole 81 through it, parallel with the barrel. A set screw 82 fixes the position of a small rod 83 which passes through the hole 81 and is 40 used as a gage. 45

The operation of the tool is as follows: Assuming that the parts occupy the positions in which they are shown in the drawings, if the shaft 25 is rotated by the crank 50 lever 17 in a clockwise direction, a tooth 90 of the cam 16 will move the hammer or striker in the barrel 11 in opposition to the spring 15 which is thus compressed. At the same time another tooth 91 of the cam acts 55 upon the cam surface 42 of the pawl carrier 40 so as to produce a rotative adjustment of the pawl carrier in opposition to the spring 48. The pawl carrier turns the quill 20 and the chuck 13 through a predetermined angle 60 by reason of the engagement of the pawl 44 with the ratchet 37. The arrangement of parts is such that the rotative adjustment of the quill corresponds to one notch of the ratchet and consequently when the pawl carrier 65 is released and returned by the spring

48 to its original position, in contact with the stop 46, the pawl will fall into the next notch of the ratchet.

After the tooth 90 of the cam has raised the hammer or striker and compressed the 70 spring, it will release the striker, if the rotation of the shaft 25 is continued, and will permit it to be thrown into percussive engagement with the inner end of the tool. This action is repeated for each tooth of the 75 cam and as a result a series of hammer blows are directed against the end of the tool. Furthermore between each blow of the striker, the tool is slightly rotated thereby producing the most desirable combination 80 for stone drilling. Any suitable tool may be mounted in the chuck and the device used for various purposes. The force of the blow struck by the striker or hammer may be adjusted by turning the nut 66 and thereby 85 changing the position of the stop 67 to vary the compression of the spring 15. The crank lever may of course be mounted on either end of the shaft 25 or two crank levers may be employed instead of one. 90

The gage 81 forms a simple and adjustable means for predetermining the depth of the hole which is drilled by the tool, the end of the gage coming into engagement with the surface of the work as shown in 95 Fig. 4 when the hole is to the proper depth.

Attention is directed to the fact that the parts of my spring hammer are comparatively few in number and are all relatively simple. The tool is furthermore easily assembled and inexpensive to construct. 100

Another advantage of my invention arises from the fact that no gears are embodied in its construction and the only screw threaded parts are small and simple and may be 105 easily manufactured on an automatic screw machine. It is obviously unnecessary to have the teeth of the ratchet 37 and the cam 16 accurately cut and in fact the cost of making this tool is small. 110

Variations in order and arrangement of parts may of course be effected within the spirit and scope of my invention and I desire that only such limitations be imposed as are indicated in the appended claims. 115

What I claim is:

1. A spring hammer comprising a barrel, a stop at one end of the barrel, a non-reciprocable chuck at the opposite end of the barrel, a striker in the barrel adjacent to the chuck, a spring interposed between the stop and the striker, means for intermittently moving the striker in opposition to the spring, a quill surrounding one end of the barrel and secured to the chuck and means dependent upon said first named means for producing a series of rotative adjustments of the quill and the chuck, said chuck being adapted to receive reciprocable drill steel. 120

2. A spring hammer comprising a barrel, a non-reciprocable chuck rotatively supported at one end, a striker in the barrel, a spring acting on the striker, a casing secured to the barrel intermediate its ends and having a boss through which the barrel extends, a quill secured to the chuck surrounding the adjacent end of the barrel and rotatively mounted in said boss, a ratchet secured to the end of the quill within the casing, a rotatable pawl carrier adjacent to said ratchet, a spring tending to hold the pawl carrier in a predetermined position, a pawl pivoted on the carrier and coöperating with the ratchet, and a single cam rotatively mounted in the casing and having a toothed periphery adapted to actuate the striker and to produce intermittent rotative movements of the ratchet and chuck, said chuck being adapted to receive reciprocable drill steel. 15 20
- 5 In witness whereof I have hereunto set my hand this 11th day of November, 1912, in the presence of two witnesses.
